PROTECTIVE FLAP FOR BICYCLE FENDERS OR SIMILAR ARTICLE

Leslie E. Tarbox, Malden, Mass.

Application November 3, 1953, Serial No. 27,441

Term of patent 14 years

(Cl. D90—5)

To all whom it may concern:

Be it known that I, Leslie E. Tarbox, a citizen of the United States, residing at Malden in the county of Middlesex in the Commonwealth of Massachusetts, have invented a new, original, and ornamental Design for a Protective Flap for Bicycle Fenders, or Similar Article, of which the following is a specification, reference being had to the accompanying drawing, forming a part thereof, in which:

Fig. 1 is a top plan view of a protective flap for bicycle fenders, or similar article, embodying my new design.

Figure 2 is a bottom plan view thereof;

Figure 3 is a side edge view thereof.

I claim:

The ornamental design for a protective flap for bicycle fenders, or similar article, substantially as shown.
